FLOATING PONTOON

Marcel Jean Tabur, Le Mans, France, assignor to
G.M.T.S.A., Le Mans, France

Filed July 1, 1971, Ser. No. 159,075

Claims priority, application France Jan. 7, 1971

Term of patent 14 years

Int. Cl. D21—03

U.S. Cl. D71—1 HH

FIG. -1

FIG. - 2

FIG. - 3

FIG. - 4

FIG. - 5

FIG. - 6

FIG. - 7

FIG. 1 is a side perspective view of a floating pontoon showing my new design;

FIG. 2 is an elevational view of the floating pontoon of the present design as seen from the right-hand side of FIG. 1 and reduced somewhat;

FIG. 3 is a front elevational view of the floating pontoon showing my new design;

FIG. 4 is an elevational view of the floating pontoon of my new design as seen from the left-hand side of FIG. 1 and reduced somewhat;

FIG. 5 is a bottom elevational view of the floating pontoon showing my new design;

FIG. 6 is an elevational end view of the floating pontoon of my new design as seen from the end opposite that shown in FIG. 3;

FIG. 7 is a top elevational view of the floating pontoon showing my new design.

I claim:

The ornamental design for a floating pontoon, as shown.
